CHRONOLOGICAL DEVICE

John Henry Willis, Norwich, England

Application July 25, 1934, Serial No. 736,829
In Great Britain June 14, 1934

8 Claims. (Cl. 58—43)

The object of this invention is to provide means for the more effective use of my patented chronological device No. 1,832,342 when issued in clock form; and in particular to enable it to show continuously the exact time to the minutest subdivision desired throughout the world on both land and sea. A further object is to obviate all need for altering the clock on the shift to and from "summertime" or any arbitrarily adopted hour.

In order to obviate the necessity for altering the clock on the shift from standard to "summertime" or daylight saving time and vice versa, it may be provided that the chart on which the time dial revolves may bear the names of places adopting different times at different periods of the year repeated in distinctive lettering, or otherwise distinguished, on the alternative meridians they adopt. Thus, while England's time would during its observance of standard time be that of meridian "0", during "summertime's" observance it would be that of meridian 15 E. Hence, a clock designed as mentioned above would need no alteration on the shift to "summertime" and vice versa, nor on ship nor air services nor on the passage from one land to another, but would always show, without change, the exact and relative times throughout the world.

To facilitate reading, any desired differentiation in the form of the meridians may be employed for directing attention to any particular meridian, as, for example, the meridians of the places the user may generally be in, or of the place or places with which the user may most frequently desire to communicate. Thus, an emphasized meridian could point to the hour observed in England during its observance of standard time, and a skeleton meridian could point to the hour during "summertime's" observance. It will be well understood that any form of mechanism (e. g. electrical or lever clockwork) may be employed for driving the dial or time ring. A simple mechanism expressly designed for this purpose comprises the ordinary revolving electrical mechanism, or spring drum with escapement control, from which the dial or time ring is revolved by friction drive, the supplementary hand or hands being operatively connected to the time dial through gearing of appropriate ratio.

One constructional embodiment of the invention is shown, by way of example only, on the accompanying sheet of drawings, whereon:—

Fig. 1 is a view of a chart and time dial of the type covered by my Patent No. 1,832,342, indicat-

ing in this particular design the supplementary hand cooperatively movable over a supplementary dial 11 bearing minute graduations, and also the further additions referred to.

Fig. 2 is a diagrammatic view of part of the mechanism for continuously rotating the hour dial 8 and minute hand 10.

Referring to the drawing:—

The primary chart member 1 is arranged in front of any convenient, power, driving mechanism, part of which is indicated diagrammatically in Fig. 2. This mechanism may be electrically or otherwise conveniently actuated; in its illustrated form, it comprises a spring drum 4, which is arranged to make one complete revolution once in every twenty-four hours and which, by means of gearing 5 and 6, is adapted to rotate a shaft 7 once in every hour. A primary time dial or ring 8, provided with time graduations representing all hours of the day and the night, is mounted on the shaft 9 of the spring drum. As shown in Fig. 1, the dial 8 is arranged in front of the primary chart member, with its centre coincident with the focal or center point 3. From this centre point 3 radiate meridian lines 15 representing time meridians, instead of geographical meridians. As the dial 8 turns, therefore, the time at all places on the chart will be automatically indicated when it correctly indicates the time at any particular place.

The shaft 7 projects forwardly through the primary chart member 1 and is provided with a supplementary hand 10, which is adapted to be rotated in front of a supplementary chart, in the form of a ring 11, divided into 60 graduations each of which represents one minute of time, and which may be either provided on the chart or on a dial affixed thereto. By such rotation of a supplementary hand 10, in cooperation with the supplementary ring chart 11, in relation to the revolving dial and chart of Patent 1,832,342, the exact time to a minute throughout the world can be indicated by this single hand.

The time dial 8 and the supplementary hand or hands or other members 10 are thus revolved simultaneously in timed relation. The hand 10 does not, however, perform the same function as the minute-hand of an ordinary clock, for there is no revolving hour-hand for cooperation therewith. Its revolutions are coordinated with the revolving time dial or ring 8, the latter being coordinated with a chart of the world, the meridians 15 of which, however, are represented in terms of its time, instead of its geography. The signal advantage of this method of recording

time is that while, with the existing clock method of revolving twin hands round a stationary dial, hundreds of hands must necessarily be needed to show times everywhere, by this new method of using a single hand in conjunction with the revolving time dial 8 and the world chart member 1, the exact time to a minute or second may be indicated by this single hand 10 throughout the world.

10 And if, for example, because, say, of its diminutive size, the dial or hour ring 8 were graduated with only the quarter and half hour scales, the exact standard times to a minute throughout the world would nevertheless be shown, if the 15 time dial or ring, during its one revolution in 24 hours, were made, by gearing, to revolve a minute-hand around a circle of 60 graduations once in an hour, because it would then show the exact number of minutes past each standard hour 20 everywhere. Furthermore, if additional hands were not desired, the exact standard time to a second throughout the world could still be indicated by a single hand. For were, say, 5-minute divisions of time marked on the time dial or ring 25 8, the hand 10 could be made by gearing to revolve once in 5 minutes round a 5-minute circle on the ring chart 11 with the seconds marked in between.

Numeral 12 shows how the further new feature, 30 the duplication of names, such as that of Great Britain, in distinctive lettering or colouring on any alternative meridian of time a country may periodically adopt, makes needless any alteration of the clock on a shift to or from "summertime" or any other adopted hour. For, since 35 the world is charted not on its geographical, but on its time meridians, the dial, without change, shows the different hour at the new time meridian on which the duplicate name appears. Thus, 40 England's time during "summertime's" observance is merely read at meridian 15 E., instead of at meridian "0".

The further feature consisting of the shaded or tinted or other distinctively marked area or 45 belt 13 will show how sea times may be indicated by the provision of an exclusive area in any desired position, marked not only with the names of the seas, but also with the solar degrees of longitude, to make instantly apparent 50 not only standard but also the mean solar times of ships at sea. These solar degrees of longitude are shown in the shaded belt on the circumference of the chart bearing the names of the seas. The position of such belt may, of course, be 55 varied.

The designations "Holland, +20" and "Newfoundland, +29" will be understood when it is reflected that the spear head of the minutes hand 10 points, at any moment, to the number of minutes it is past each standard hour everywhere. As the time of Holland and Newfoundland is in advance of that of their nearest standard meridians, the respective figures +20 and +29 show the number of minutes that must 60 be added to the reading of the hand to show the time at these particular places. The people of Holland, for example, prefer to observe the solar time of their capital, instead of the standard time of the time zone in which their country 65 is positioned. Just to the right of the zero time meridian 15, therefore, the primary chart member 1 contains a separate time meridian, upon which is charted "Holland, +20". And since 70 the revolving dial 8 does not carry such small

subdivisions of time as minutes, and it might therefore be difficult to gauge from it Holland's time to an exact minute, "+20" is added to the name to show that its exact minute at any moment, is 20 in advance of the reading of the 5 hand.

The primary chart member 1 contains other such time meridians, different from the standard time according to zones, but corresponding to times adopted by particular localities; and such other times are not necessarily local mean solar times. Reference may be made, for example, not only to the special time meridians associated with "Holland, +20" and "Newfoundland, +29", but also "Venezuela", between the 45-degree and 15 the 90-degree time meridians. In all cases, the present invention makes it possible to read the exact adopted time observed by everybody in the world, and this whether the adopted time is standard, solar, daylight-saving, or any other 20 individual time; in all cases, in manufacturing the chart, the name of the country or place in which the observer or user of the chart is located is placed opposite, i. e., in line with the meridian of the particular time adopted by such observer. These figures +20 and +29 are not strictly necessary; for the time divisions on the dial show, for example, that, when it is noon on the Greenwich meridian, it is 20 minutes past noon in Holland; but by stating the number of minutes to be added to the reading of the spear head of the minutes hand 10 in half a dozen exceptional and particular cases, it saves one the trouble of referring to the time divisions on the dial.

Though the said spear head of the minutes hand 10 shows the number of minutes past the hours, or to the nearest hour, of all places observing standard or adopted time, furthermore, its reverse end shows the number of minutes past the hour in all places, like India, the noon of which lies midway between the standard meridians. When, for example, it is exactly 5 p. m. in Western Siberia, the reverse end of the minutes hand automatically shows that it is 5:30 p. m. in India, and when it is 15 minutes past 5 in Western Siberia, the reverse end of the minutes hand automatically shows it is 5:45 p. m. in India.

The additional feature consisting of an asterisk 50 14 at the point of midnight on the dial, indicates at what point the new day is commencing in its sweep round the world, and marks off in the anti-clockwise revolution of the dial, the area of the old day from the area of the new.

The further feature of differentiated meridians 55 15 or 30 illustrates a means of making more prominent the particular time area the user may be in, or in frequent communication with, or in differentiating between the different times adopted 60 by countries at different periods of the year. The meridian 15 may correspond to solar time and the meridian 30 to daylight-saving time for the same countries.

Numeral 16 shows how by the addition of the word "noon" in conjunction with a curved arrow, the position of noon and the direction of its rotation are made more immediately apparent, thus indicating at any moment which places are in advance of noon—a. m.—or afternoon—p. m.

Numeral 17 shows how, by a differentiation in shading, the main continental areas are made more easily distinguishable, to facilitate reading.

The dial 8 may be shaded at 18 to indicate the hours, usually of darkness, between 6 o'clock

in the evening and 6 o'clock in the morning and it may further be provided with a black portion 19 to indicate the hours between 6 o'clock in the evening and midnight.

5 Moreover, the dial or time ring may be revolved clockwise by making the numerals run backward and by altering the design of the chart so that meridian 15° E. would appear to the left of the Greenwich meridian and America 10 would appear on the right of the chart, and so on.

I claim:

1. A chronological device of the kind described comprising a primary chart member provided with a plurality of lines of meridian radiating from a center to represent meridians of standard and other adopted time, each marked with portions of the world adopting such meridians as their meridians of standard and other adopted 15 time, a primary dial member, means for revolving the primary dial member once in every twenty-four hours the primary chart member and the primary dial member being provided with means for together indicating the hours of the 20 day or night or fractions thereof during their relative movement, whereby, during such relative movement, the primary chart member and the primary dial member simultaneously indicate the said standard and other adopted time at any instant, in terms of hours and fractions of an hour, corresponding to all places marked on the primary chart member, a supplementary chart provided with graduations to indicate subdivisions of the said hours and fractions of an hour indicated by the primary chart member and the primary dial member, a supplementary member cooperative with the supplementary chart, and means for revolving the supplementary member in timed relation to the primary dial member 30 to indicate the said subdivisions of time after the hour indicated by the primary chart member and the primary dial member.

2. A chronological device of the kind described comprising a primary chart member provided with a plurality of lines of meridian radiating from a center to represent adopted-time meridians, each marked with portions of the world adopting such meridians as their meridians of adopted time, a primary dial member, means for continuously revolving the primary dial member once in every twenty-four hours, the primary chart member and the primary dial member being provided with means for together indicating the hours of the day or night or fractions thereof during their relative movement, whereby, during such relative movement, the primary chart member and the primary dial member simultaneously indicate the said adopted time at any instant, in terms of hours and fractions of an hour, corresponding to all places marked on the primary chart member, a supplementary chart provided with graduations to indicate subdivisions of the said hours and fractions of an hour indicated by the primary chart member and the primary dial member, a supplementary member cooperative with the supplementary chart, and means connecting the supplementary member with the primary dial member in the ratio of twenty-four to one for revolving the supplementary member once every hour to indicate the said subdivisions of time after the hour indicated by the primary chart member and the primary dial member.

3. A chronological device as specified in claim 2 75 in which the supplementary member is operative-

ly connected with the primary dial member so as to be revolved in proximity to the graduations of the supplementary chart about a center different from the center of revolution of the primary dial member.

4. A chronological device as specified in claim 2 in which the markings corresponding to various portions of the world are duplicated on different meridians to indicate different adopted times for the said portions of the world.

5. A chronological device as specified in claim 2 in which the primary dial member is provided with a gear and the graduations of the supplementary chart correspond to minutes divisions of the hour and the supplementary member is operatively connected with the primary dial member so as to revolve against the said minutes divisions, the said supplementary member being pivoted to revolve about a center different from the center of revolution of the primary dial member, the operative connections of the supplementary member comprising a single gear meshing with the said gear of the primary dial, and the said supplementary member extending across the entire diameter of the supplementary chart, whereby, when one end of the supplementary member shows minutes past the hours of places observing the said adopted times, its reverse end will show simultaneously the minutes past the hours of places observing intermediate times.

6. A chronological device of the kind described comprising a primary chart member provided with a plurality of lines of meridian radiating from a center to represent adopted-time meridians, each marked with portions of the world adopting such meridians as their meridians of adopted time, a primary dial member, means for relatively moving the primary chart member and the primary dial member, the primary chart member and the primary dial member being provided with means for together indicating the hours of the day or night or fractions thereof during their relative movement, the primary chart member and the primary dial member simultaneously indicate the said adopted time at any instant, in terms of hours and fractions of an hour, corresponding to all places marked on the primary chart member, two cooperative supplementary elements, namely, a supplementary chart and a supplementary member cooperative with the supplementary chart, the supplementary chart being provided with graduations to indicate the minutes of only a single hour, and means for relatively moving the supplementary elements in timed relation to the relative movement of the primary chart member and the primary dial member throughout one complete cycle once every hour to indicate minutes of time after the hour indicated by the primary chart member and the primary dial member.

7. A chronological device of the kind described comprising a primary chart member provided with a plurality of lines of meridian radiating from a center to represent adopted-time meridians, each marked with portions of the world adopting such meridians as their meridians of adopted time, a primary dial member provided with markings indicating the hours of the day or night or fractions thereof arranged consecutively in a clock-wise direction, means for continuously moving the primary dial member over the chart member in an anti-clock-wise direction, whereby the primary dial member will indicate on the chart member the said adopted time at

any instant, in terms of hours and fractions of an hour, corresponding to all places marked on the primary chart member, a supplementary chart, a supplementary member cooperative with the supplementary chart, the supplementary chart being provided with graduations to indicate minute divisions of time than can be conveniently indicated by the primary dial member on the primary chart member, and means connecting the supplementary member with the moving means to cause the supplementary member to be moved continuously in the clock-wise direction over the supplementary chart in timed relation to the movement of the primary dial member, whereby the supplementary member

will indicate on the supplementary chart minute divisions of time after the hour indicated by the primary dial member on the primary chart member to indicate the said adopted time throughout the world to a small fraction of time.

8. A chronological device as specified in claim 6 in which the supplementary member extends across the entire diameter of the supplementary chart, whereby, when one end of the supplementary member shows minutes past the hours of 10 places observing the said adopted times, its reverse end will show simultaneously the minutes past the hours of places observing intermediate times.

JOHN H. WILLIS. 15
